(57) **CLAIM**

The ornamental design for a fountain pen, as shown and described.

DESCRIPTION

FIG. 1 is a front perspective view of the fountain pen showing my new design;

FIG. 2 is a front elevational view thereof;

FIG. 3 is a rear elevational view thereof;

FIG. 4 is a right-side view thereof;

FIG. 5 is a left-side view thereof;

FIG. 6 is a top plan view thereof;

FIG. 7 is a bottom plan view thereof;

FIG. 8 is a front perspective view of the fountain pen of FIG. 1 with the cap of the fountain pen detached;

FIG. 9 is a front perspective view of the fountain pen of FIG. 1 in a disassembled state;

FIG. 10 is a cross-sectional view taken along the line 10-10 of FIG. 2;

FIG. 11 is a front perspective view of the fountain pen of FIG. 1 in an alternate configuration;

FIG. 12 is a front perspective view of the fountain pen of FIG. 11 in an alternate configuration; and,

FIG. 13 is a cross-sectional view taken along the line 13-13 of FIG. 11.

The broken lines shown in the drawings illustrate portions of the fountain pen that form no part of the claimed design.

1 Claim, 12 Drawing Sheets
